CLAIM

The ornamental design for wireless headset, as shown and described.

DESCRIPTION

FIG. 1 is a front view of a portion of a wireless headset. FIG. 2 is a rear view of the portion of the wireless headset of FIG. 1.

FIG. 3 is a left side view of the portion of the wireless headset of FIG. 1.

FIG. 4 is a right side view of the portion of the wireless headset of FIG. 1.

FIG. 5 is a bottom view of the portion of the wireless headset of FIG. 1.

FIG. 6 is a top view of the portion of the wireless headset of FIG. 1.

FIG. 7 is a perspective view of the portion of the wireless headset of FIG. 1.

FIG. 8 is a front view of a portion of a wireless headset.

FIG. 9 is a rear view of the portion of the wireless headset of FIG. 8.

FIG. 10 is a left side view of the portion of the wireless headset of FIG. 8.

FIG. 11 is a right side view of the portion of the wireless headset of FIG. 8.

FIG. 12 is a bottom view of the portion of the wireless headset of FIG. 8.

FIG. 13 is a top view of the portion of the wireless headset of FIG. 8; and,

FIG. 14 is a perspective view of the portion of the wireless headset of FIG. 8.

The broken line showing of the environment is for illustrative purposes only and forms no part of the claimed design.

1 Claim, 14 Drawing Sheets
